UNITED STATES PATENT OFFICE.

PETER J. DUFFY, OF HOUSTON, TEXAS.

DRILL.

Application filed March 4, 1924. Serial No. 696,761.

This invention relates to new and useful improvements in a drill.

One object of the invention resides in the provision of a drill particularly designed for use in drilling through soft formations, but which may also be used in drilling through rock or other hard formations,

Another object of the invention is to provide a drill of the character described which is of such construction and contour that it will drill a comparatively straight bore.

A further feature of the invention resides in the provision of a drill having a detachable pilot, and detachable side cutters which may be readily renewed in case they become worn or broken.

A still further feature of the invention resides in the provision of a drill having a central spiralled conveyor, so that when the pilot is removed a core will be formed, by the drill, and conveyed up into a core barrel with which the drill is equipped.

With the above and other objects in view, this invention has particular relation to certain novel features of construction, operation and arrangement of parts, an example of which is given in this specification and illustrated in the accompanying drawings, wherein:

- 30 Figure 1 shows a plan view of the drill.
- Figure 2 shows a bottom end view.
- Figure 3 shows a vertical sectional view.
- Figure 4 shows a perspective view of one of the side cutters.
- Figure 5 shows a side view of the pilot bit.
- Figure 6 shows a point view thereof;
- Figure 7 shows a side view, partly in section, of a supplemental core conveyor, which may be employed; and Figure 8 is a plug adapted to be screwed into the drill head 1, in lieu of pipe 6.

Referring now more particularly to the drawings, wherein like numerals of reference designate similar parts in each of the figures, the numeral 1 designates the drill head whose upper end is slightly reduced and outwardly threaded to receive the drill collar 2, by means of which the drill is attached to the drill stem (not shown). The head, beneath said collar, tapers slightly downwardly, or is of an inverted frusto-conical contour. The tapered part of the head has the outside vertical dovetailed grooves 3, spaced apart there-around. Side cutters 4, 4' are fitted into these respec-

tive grooves, the inner sides of the cutters being dovetailed to fit into the grooves. 55

The sides of the grooves, and likewise the sides of the cutters are contracted or converge downwardly and the cutters are fitted into the grooves from the upper ends of the latter and wedge therein. The drill collar 2 is then screwed onto the shank of the drill and its lower end abuts against the upper ends of the cutters and locks them against detachment. The outer edges of the cutters are extended forwardly, as at 5, and formed with sharp cutting, or reaming edges, which converge at their lower ends and project some distance below the drill head. The cutters 4' have their cutting edges serrated, the teeth of some of said cutters being staggered with relation to the teeth of the other cutters. 70

Within the drill stem, and screwed into the upper end of the head, there is a core barrel 6, of any desired length whose upper end may be closed in any preferred manner to exclude water or foreign matter and prevent the same from mingling with the core. 75 Aligned with the core barrel there is a vertical bore 7, through the head, whose walls are provided with a spiral 8, forming a core conveyor. As the bit progresses through the strata, the projecting lower ends of the cutters 4, 4' form a core which passes up into the bore 7, and is caught by the spiralled conveyor 8, and carried on upwardly and finally delivered into the barrel 6. The bore 7 is slightly enlarged upwardly so that the core will not bind, or become stuck therein. 85

If a smaller core be desired, a supplemental core conveyor 9 may be screwed downwardly into the bore 7. This conveyor 9 has a vertical bore provided with a spiral 10, forming a core conveyor to take hold of and elevate the core, relative to the drill, as the drill rotates in progress of the work. The bore 7 and the supplemental conveyor 9 are provided with keyways 7', 9' adapted to register when the conveyor 9 is screwed home and to receive a key to prevent the unscrewing of the conveyor 9. 90

The lower end of the supplemental conveyor 9 is toothed, so as to reduce the size of the core formed by the cutters 4, 4', in order that the reduced core will enter the conveyor 9. 105

When it is desired to use the device as a drill only, a pilot 12 is threaded up into the

lower internally threaded end 13, of the bore 7. This pilot will hold the drill centered and a straight bore will thus be made. This 5 pilot may be of any desired form. Preferably it is substantially conical in shape, and provided with radiating cutters 14, as shown. The head has the usual water courses 15 to admit flushing water to the cutting edges of the cutters.

10 As illustrated, the drill is shown with six detachable cutters, but it is to be noted that any desired number may be used, and these cutters may vary in width, so that different sizes of bores may be drilled with the same 15 head.

When the drill is used for taking a core, particularly in deep drilling, it may be found desirable to reduce the bore and this may be done by removing the cutters altogether. 20 The bearing shoulders, behind the respective cutters are formed with sufficiently sharp cutting edges to ream out the bore during this core taking process, or very narrow blades may be used, so as to reduce the bore during 25 the core taking process, to the desired diameter.

It may be further noted that when the drill is not being used as a core taker the core barrel 6 may be removed from the drill head, and 30 a plug as 16 screwed in the upper end of said

head in an obvious manner which will greatly strengthen the drill shank and lessen the liability of its breaking off.

It is to be further noted that the forward sides of the cutters 4, 4' decline rearwardly 35 or are slightly spiralled relative to the head, so that the cuttings will more readily travel up said declining sides and faces and will not be so liable to congest against the cutters.

It is further to be noted that the cutting 40 edges of the cutters may be inset with diamonds as illustrated in Figure 4, or said cutters may be made of any other hard material desired.

What I claim is:—

1. A drill including a head, formed with a vertical bore having its inner walls formed into a spiralled conveyor, and approximately vertical side cutters carried by the head whose edges recede toward both ends thereof 50 and, whose lower ends extend below the head.

2. In a drill, a head having a vertical bore formed into a spiralled conveyor and dovetailed side cutters carried by the head, and formed with cutting edges which recede 55 toward each end thereof.

In testimony whereof I have signed my name to this specification.

PETER J. DUFFY.
